PUNCH ATTACHMENT

Filed Dec. 30, 1929

INVENTOR.

Arthur L. Kuhlman

Frank G. Farman

ATTORNEY.

UNITED STATES PATENT OFFICE

ARTHUR L. KUHLMAN, OF DETROIT, MICHIGAN

PUNCH ATTACHMENT

Application filed December 30, 1929. Serial No. 417,457.

This invention relates to attachments for screw drivers, such attachments being in the form of punches, chisels, reduced screw driver blades, and similar tools, and particularly to an attachment which can be quickly and easily shifted into and out of working position.

For explanatory purposes I shall show and describe a punch attachment particularly adapted for attachment to a screw driver, so that a hole may be punched in the wood for starting a wood screw, after which the attachment is shifted upwardly, and the screw driver blade utilized for driving the screw home.

Another object is to provide a combination tool, which can be used as a punch, ice pick, or for various other purposes, and which is formed of resilient material so that it will be frictionally held in its retracted position on the screw driver shank.

The above and other objects will appear as the specification progresses, reference being had to the accompanying drawings, in which I have shown the preferred embodiment of my invention, and in which like reference numerals indicate like parts throughout the several views thereof.

In the drawings:

Fig. 1 is a view of a conventional screw driver showing the punch attachment in position for punching a hole.

Fig. 2 is an edge view of the device shown in Fig. 1.

Fig. 3 is a detail back view of the punch attachment.

Fig. 4 is a vertical sectional view thereof.

Fig. 5 is an end view of the device.

The advantages of a combination tool of this nature will be readily understood by carpenters, electricians, and others having occasion to seat wood screws, etc., as it eliminates the use of one tool when driving screws when seated on a ladder, or in places where the footing is insecure. It is also necessary to reach in the pocket, belt, or to a ledge for individual tools, thereby saving time and eliminating the risk of falling as the result of reaching and the consequent loss of balance.

Referring now particularly to the drawings, in which I have shown the preferred embodiment of my invention, the numeral 5 indicates the punch attachment which is preferably in the form of a stamping, the lower end 6 being pointed, and a lip 7 is punched in the main body and is bent outwardly as shown and for a purpose to be presently described, a raised rib 8 being formed in the metal directly below the lip for reinforcing the point.

The upper end of the main body is bent at an angle as clearly shown at 9 in Fig. 4 of the drawings, and a relatively light stamping 10 is secured to the upper end thereof by means of rivets 11, the side walls or wings 12 of said stamping extending outwardly and converging towards each other, the free ends 13, being rolled and normally lying in close proximity so that when a screw driver blade 14 is inserted therebetween, a resilient gripping action will result, so that when not in use the attachment may be shifted upwardly on the shank so that the blade may be used in the conventional manner.

In assembling the attachment on a screw driver, the blade is turned at a slight angle and forced downwardly between the wings 12 until the blade 15 seats between the lip 7 and the main body, and the tool is now ready to be used as a punch. When it is desired to utilize the blade of the screw driver to drive a screw, the blade is forced out of engagement with the lip, and the attachment forced upwardly on the shank, the resiliency of the metal insuring it being frictionally held in adjusted position.

From the foregoing description it will be obvious that I have perfected a very simple, inexpensive, and convenient attachment.

What I claim is:—

1. An attachment for a screw driver comprising a stamped plate having an outwardly bent lip punched from the main body for engaging the end of a screw driver blade, and a substantially U-shaped resilient stamping secured to the upper end of said plate and embracing the said screw driver shank for holding said attachment on a screw driver.

2. An attachment for a screw driver comprising a stamped plate adapted to be mounted on the shank of the screw driver and shiftable into or out of engagement with the end of the blade, means on said plate for engaging the lower end of the screw driver blade, and resilient wings on said attachment and embracing said shank for holding it in position on said screw driver.
- 10 3. A punch attachment for a conventional screw driver comprising a stamped plate having a pointed lower end, a lip on the face thereof for engaging the end of a screw driver blade, and resilient inwardly converging wings on the upper end of the plate for detachably engaging the shank of a screw driver.
- 15 4. A punch attachment for a screw driver comprising a plate, the upper end of which is bent an angle with relation to the body, the lower end being pointed, a lip intermediate the length of the plate and punched therefrom, and substantially U-shaped resilient wings on the upper end of the plate for detachably embracing a screw driver blade.
- 20 5. A punch attachment for a conventional screw driver comprising a plate having a pointed lower end, resilient wings secured on the upper end of said plate for resiliently and detachably embracing a screw driver blade, and an integral lip on the face of the plate for engaging the end of a screw driver blade.
- 25 35. In testimony whereof I hereunto affix my signature.

ARTHUR L. KUHLMAN.
